UNITED STATES PATENT OFFICE.

ALEXANDER DAVIDSON, OF NEW YORK, N. Y., AND CHARLES G. ARMSTRONG, OF CHICAGO, ILLINOIS; SAID ARMSTRONG ASSIGNOR TO SAID DAVIDSON.

ELECTRIC TIME CHECK AND RECORDER.

SPECIFICATION forming part of Letters Patent No. 579,473, dated March 23, 1897.

Application filed January 25, 1896. Serial No. 576,843. (No model.)

To all whom it may concern:

Be it known that we, ALEXANDER DAVIDSON, of New York, in the county of New York and State of New York, and CHARLES G. ARMSTRONG, of Chicago, in the county of Cook and State of Illinois, have invented a new and useful Improvement in Electric Time Checks and Recorders, of which the following is a specification.

Our invention is in the nature of an electric time check and recorder designed, mainly, for the special use hereinafter indicated, but applicable also to other uses.

In another application for a patent filed by us of even date herewith we have described and shown an electric ticket-selling device in which reserved-seat tickets could be sold at several different points without interference and in which the parts are so organized by means of a series of annunciators, synchronized clocks, and commutators that the sale of any ticket at any station immediately and automatically transmits a signal to the annunciators of the other stations, causing a drop to fall that indicates to each of these stations that a certain ticket has been sold, and hence is not to be sold by them again. Our present invention is an extension and development of this idea, in which a permanent record is made of the sales of tickets and the time thereof and also a record of any error (and the time thereof)—such, for instance, as that made by two agents pulling tickets bearing the same number—and also, further, whereby a continuous record is made of the proper synchronism of the clocks, which synchronism is essential to the success of the whole system.

Our invention consists in the peculiar instrumentalities for carrying out these results, as will be hereinafter fully described with reference to the drawing, in which the figure is a diagram view of two stations with their annunciators, synchronous clocks, time-recorders, and batteries.

CC are two clock-dials at two different stations, having two heads C'C', revolving in synchronism under the influence of a single master-clock, (not shown,) and an electric circuit closed by the master-clock at regular and short intervals through the magnets A'A'', as more fully shown in our previous ap-

plication. These magnets, through the armatures C⁴, springs C⁵, pawls C⁶, and ratchet-wheels C² on the hands C' of the clock-dial, impart an exactly equal rotary motion to these hands. These dials have insulated contact-plates c distributed around their faces and corresponding in number to the whole number of tickets to be sold and numbered accordingly and acting as commutator-plates with the revolving hand.

At each station there is an annunciator having a series of ticket-holders h h', corresponding in number to the commutator-plates. Each ticket-holder has an electromagnet D, bearing a contact-spring d, connected to one of its terminals and controlling a drop-shutter B².

E is a push-button whose stem has a small front part e³ and an enlarged middle part, the middle of which e is of brass, with non-conducting hubs e' e² on opposite sides, and whose rear end is surrounded by a spring e⁴, that pushes it forward. A head e⁵ in its rear end is adapted to engage a latch f on the armature F and be locked by it in its "pushed-in" position.

G and G' are batteries, and g g' are contact-springs beneath the push-button.

Now when a ticket is to be sold, say at station No. 1, push-button E is forced in and the spring h² of jaw h' drops down onto the small part e³ of the stem and releases the grip of the jaw on the ticket, so that it can be pulled out. As the push-button goes in its rear end is caught and held by latch f of armature F and is left for a moment with springs d and g' connected through the brass hub e, and the current from battery G then flows as follows: from the positive side of battery G to r², to electromagnet R, back through r' to contact-spring g', and thence exactly as shown in our previous application—i. e., to e, spring d, magnet D, (dropping shutter B²), to wire 17, commutator-plate 6, hand C', line-wire 16 18 19 to hand C' of the next station and (this hand being in perfect synchronism with the other hand) through commutator-plate 6, wire 17, magnet D, spring d, and (push-button being out) through brass e, to spring g, wire 13, to line 2, back to 1 and the negative side of the battery. The result will

be that magnet D at station No. 2 will be energized to drop its shutter simultaneously with that at the selling-station, and this gives an indication to the remote station that a ticket (No. 6, as shown) has been sold. At the same time that this indication is given to the remote station the electromagnet R at the selling-station is energized, and its elongated armature *r*, bearing a pencil or a point, makes a dot on the revolving dial X of an ordinary watchman's clock, and the succession of these dots at closer or more remote intervals shows the time of the sales of the tickets during the day, showing at what time during the day the most tickets are sold and recording the sale of every ticket at that station. Beside the same dial X there is another electromagnet S, which is intended to record an interference between two stations, if by chance two agents at different points should draw out tickets of the same number. A separate line-wire *s'* and battery B are used for this, and one jaw *h* of the ticket-holder is connected by shunt-wire *s*³ direct to wire 17, (without going through the magnet D.) The other jaw *h'* is connected by wire *s*² to magnet S, and thence by *s'* to battery B. Now it being understood that the two jaws *h h'* at each station are made the terminals of the circuit of battery B, and that it is necessary that both pairs of jaws should be closed by the simultaneous (or successive) withdrawal of the ticket bearing the same number at two stations in order to close this circuit, the following result takes place: When two such tickets are withdrawn and the two pairs of jaws *h h'* close said circuit, the current flows from positive pole of battery B to *s'*, magnet S, wire *s*², jaw *h'*, jaw *h*, shunt-wire *s*³, wire 17, plate 6, hand C', line-wire 16 18 19 to the other station, (No. 2,) to hand C', plate 6, wire 17, shunt-wire *s*³, through jaws *h h'*, wire *s*², magnet S, wire *s'*, to the negative side of battery B, causing the magnets S at each station to operate their armatures and record the time of such interference upon the revolving dials X.

Another feature, and one of the greatest importance, is the means for determining constantly the accurately-operative conditions of the several synchronized clocks C C. The whole system, it will be remembered, is predicated upon the necessity of having every hand C' in its revolution touch any one plate 6 at the same instant of time that every other hand touches its corresponding plate 6, and if for any reason these hands should get out of synchronism this fact should be instantly known and the discrepancy corrected.

To instantly advise the agent of such lack of synchronism, we provide the electromagnet T and its armature *t*, which latter is extended to the dial and provided with a pencil or a point, and which, during the accurate and normal operation of the system, vibrates constantly, making a succession of dots on the dial, but which, if the hands C' C' get out of synchronism, instantly ceases to vibrate.

To accomplish the desired result, each synchronous-clock dial is provided with a special commutator-plate *c*², which has no connection with the annunciator and ticket-selling devices, but is connected by a wire *t*² with the magnet T, the other side of the magnet being connected, through wire *t' s'*, with the battery B. If now the commutator-hand C' touches the plate *c*² at the same instant at each station, the magnet T will be worked and a dot recorded, but if they do not touch at the same instant the magnets T cease to vibrate.

Assuming the circuit to be closed through *c*² and *t*² at the same instant at both stations, the current will flow as follows: from the positive side of battery B to wires *s'* and *t*, to magnet T of station No. 1, wire *t*², plate *c*², hand C', line 16 18 19, to hand C' of the other station, to plate *c*², wire *t*², magnet T of that station, and through wires *t' s'* to the negative side of battery B, and, the current being closed simultaneously at both stations through plates *c*², both magnets T will vibrate at each closure and register a dot through its armature *t* on the dial X; but if one hand C' is in advance of or behind the other then this circuit cannot be completed, for it must be closed at both points *c*² at the same time. The result will be that just as soon as the clocks get out of synchronism the magnet T will apprise the agent of that fact by ceasing to vibrate its armature, and the time at which this occurred will be recorded by the dial.

Although mainly intended for use with the ticket-selling system, we would state that some of the features of this device may be used for other purposes. Thus, for instance, the device for noting the lack of synchronism in clocks is broadly applicable, and we do not limit ourselves to the special application shown.

Having thus described our invention, what we claim as new, and desire to secure by Letters Patent, is—

1. The combination with a set of synchronized clocks; of a battery-circuit and electromagnet with pointed armature, a watchman's time-dial arranged beneath the armature to be acted upon thereby, a special commutator-plate arranged on each of the synchronous clocks and connected to said circuit, whereby the same is closed and a record made by the magnet-armature when the clocks are in synchronism, and the record is discontinued when the clocks are out of synchronism substantially as and for the purpose described.

2. A ticket-selling device, comprising a set of annunciators, ticket-holders controlling the same, synchronized clocks and commutators with batteries and circuit-wires arranged as described to indicate automatically to a remote station the sale of any ticket at the selling-station, in combination with a device for detecting a lack of synchronism in the clocks substantially as shown and described.

3. A ticket-selling device comprising a set of annunciators, synchronized clocks and

commutators with batteries and circuit-wires arranged as described to indicate automatically to a remote station the sale of any ticket at the selling-station; in combination with a 5 watchman's time-dial, and a magnet and armature operating upon the same and placed within a loop of the main operating-circuit for the purpose of recording the tickets sold and the times thereof substantially as and 10 for the purpose described.

4. A ticket-selling device comprising a set of annunciators, synchronized clocks and commutators, with batteries and circuit-wires arranged as described to indicate automatically 15 to a remote station the sale of any ticket at the selling-station; in combination with a

watchman's time-dial, and a magnet and armature operating thereupon, and a separate battery and circuit the terminals of which latter are made through two insulated jaws 20 of the ticket-holder whereby the simultaneous or successive withdrawal of a similarly-numbered ticket at two different points is made to close a circuit and record the time of such interference upon the watchman's time-dial 25 substantially as and for the purpose described.
